UNITED STATES PATENT OFFICE.

NICK ORLOFF, OF SPARROWS POINT, MARYLAND.

PORTABLE CARRIER.

1,307,597.

Specification of Letters Patent. Patented June 24, 1919.

Application filed June 11, 1918. Serial No. 239,421.

To all whom it may concern:

Be it known that I, NICK ORLOFF, a citizen of Russia, residing at Sparrows Point, in the county of Baltimore and State of Maryland, have invented certain new and useful Improvements in Portable Carriers, of which the following is a specification.

This invention relates to improvements in portable carriers of that construction which 10 renders the carrying of the injured or sick person in an efficient manner.

The object of the invention is the provision of a portable carrier of such construction as to render it capable of being carried 15 by a single person such as a soldier, Red-Cross nurse or the like and capable of being readily positioned about a patient and the carrier and patient strapped to the back of another person.

20 A further object of this invention is to provide a portable carrier capable of being used in place of stretchers or the like and is of such a construction as to be permitted to be carried as a knapsack upon the back of the soldier, sailor or the like and may be readily converted into a supporting stretcher for holding a wounded or injured person to the back of a soldier, sailor or the like.

With these and other objects in view the 30 invention consists in the novel combination, construction and arrangement of parts hereinafter more fully described, and set forth in the claims hereto appended.

In the drawings forming a part of this 35 application and in which like reference characters refer to corresponding parts throughout the several views.

Figure 1 is a side elevation illustrating the application and use of my improved 40 portable carrier.

Fig. 2 is a plan view of the seat portion of the carrier.

Fig. 3 is a perspective view of the carrier in assembled position and ready for use.

45 Fig. 4 is a fragmentary front elevation of an adjusting device or the straps of the carrier.

Fig. 5 is a fragmentary longitudinal sectional view of the adjusting device.

50 Fig. 6 is a side elevation of the seat portion of the carrier.

Fig. 7 is a modified form illustrating the seat portion converted into a pack or knapsack and adapted to be fastened to the back 55 of the user and

Fig. 8 is a perspective view of another

slightly modified form illustrating the knapsack or bag and its attachment for holding the same to the side of the person.

Referring to the drawings the numeral 5 60 indicates a substantial triangular-shaped piece of cloth or other fabric forming the body of my carrier. The side edges of the body are folded back upon themselves and stitched as at 6 to reinforce the same and 65 strengthen the side edges. The larger end of said body is also folded and stitched as at 7 to reinforce and strengthen that portion of the body. The apex of the body is provided with a plurality of radially and inwardly extending plaits 8 so as to cause the apex to have a slight nicely tapering shape.

A pair of supporting straps 9 are secured to each corner of the apex of the body as at 10. The free ends of these straps are extended through the guides 9' formed on the innerside and at each end of the larger portion of the body 5. These straps are then extended over the right and left shoulders of a person designated B in the drawings 80 and are crossed as at C as illustrated in Fig. 1. The free ends of the straps 9 are then adjustably secured to the straps 11 secured to each end of the larger end of the body as at 12 as illustrated in Fig. 6. Each of the 85 straps 11 is provided with buckles 13 to adjustably receive the terminals of the shoulder straps 9. Each of the shoulder straps 9 are provided adjacent their terminals with a suitable adjusting device 14 of any desired 90 form so that the straps 9 may be readily taken up or let out to fit persons of various sizes.

The body 5 is provided at its larger end on the outer side thereof with the spaced guides 95 15 through which guides extends the belt 16 which belt has one end secured to the seat portion as at 17 and its free end adjustably secured to a buckle 18 secured to the body as at 19 at a point remote from the securing 100 of the belt thereto. It will be readily apparent that by virtue of this belt 16 and buckle 18 the enlarged portion of the body may be adjusted about the waist-line of the injured person designated D in Fig. 1 of the 105 drawings.

In the use of the device the straps 9 are extended through their respective guides 9' it being understood that there is a strap 9 at the right and left hand corner of the 110 apex of the seat portion and each right and left handed strap extends through the right

and left handed guide 9' secured at the right and left hand corners of the larger end of the body. The straps are then extended across the right and left shoulders 5 of the carrier and are crossed at the front of the carrier B thus the terminal of the right hand strap 9 will be fastened in a buckle 13 carried by the left hand strap 11 at the left hand corner of the seat portion.

10 It will be apparent that the person wounded or injured is arranged within the body 5 with his legs projecting through the openings formed by the bending up of the apex and the connecting of the apex with the 15 larger end of the body. The straps are then arranged over the shoulders of the carrier B and fastened to the straps 11 through the medium of the buckles 13 and the patient or injured person is then nicely positioned 20 upon the back of the carrier B and may be readily transported to a base hospital or the like.

In the modification shown in Fig. 7 the body 5 having the belt 16, buckle 18 carrying strap 19 shoulder straps 9 and fastening straps 11 are used. This modification represents the forming of the carrier into a bag or knapsack and to accomplish the same the strap 16 is adjusted through the buckle 30 18 to provide the plaits 20, this drawing the side edges of the carrier together and the side edges are closed by lacing one edge to the other edge as illustrated at 21 and the apex of the seat portion and plaited portion 35 of the larger end of the seat portion forms the opening to the interior of the bag or the like. By virtue of the straps 9 and 11 this bag may be readily suspended from the shoulders and hung against the back of a 40 person.

In the modification illustrated in Fig. 8, I describe and illustrate a slightly new form of bag. This bag has all of the elements of the form shown in Fig. 7 and is similarly 45 assembled but instead of using both pairs of straps 9 and 11, only one strap of each pair is necessary to support the bag to a person. To accomplish this change, I secure to the inactive strap 9 near its point of connection to the apex of the body a locking loop 21' and this loop when assembling the bag is drawn beyond the guide loop 9' and a pin 22 is placed transversely through the locking loop 21' to hold the inactive strap 50 55 against rearward sliding movement, it being understood, of course, that the free end of

this strap is left lying in the bag. The fastening of this strap in this manner also serves to hold one side edge of the bag together in connection with the lacings. It now only remains to fasten the free ends of the active straps 9 and 11 together so that the bag may be supported or suspended on a person.

It will be obvious that these bags may be 65 filled with rations of the soldiers or sailors or may also be packed with first-aid equipment and the bag may be readily removed from the back of the user and converted into the portable carrier or stretcher by simply 70 removing the lacers 21, unfastening the belt 16 from the buckle 18 and arranging the straps 9 in the manner previously described.

Having thus described by invention, what I claim as new is:—

1. A combined portable carrier and bag comprising a flexible body, supporting straps connected to each end of said body, adjusting means at one end of said body, and means for connecting the side edges of said 80 body together whereby the carrier is converted into a bag.

2. A combined portable carrier and bag comprising a flexible body, supporting straps secured to each end of said body, guide loops 85 for certain of said straps and secured to the body, means for connecting the free ends of said straps together to permit the carrier to be attached to a person, adjusting means attached to one end of said body, and means 90 for connecting the sides of said body together and said means in coöperation with said straps and adjusting means converting the carrier into a bag.

3. A combined portable carrying bag comprising a substantially triangular-shaped flexible body, a strap attached to each corner of the larger end of said body, a strap attached to each corner of the apex of said body, guide loops secured to the larger end 100 of said body at the corners thereof, straps at the apex of the body extended through said guide loops to form a receptacle, means on the free ends of said straps whereby the carrier may be suspended to a person, adjusting means connected to the larger end of said body, and means for fastening the side edges of said body together, said means in coöperation with said straps and adjusting means converting the carrier into a bag. 110

In testimony whereof I affix my signature.

NICK ORLOFF.
